GARMENT FINISHING APPARATUS

John H. Richa and Frank E. Hanson,
Kansas City, Mo.

Application March 10, 1947, Serial No. 733,576

15 Claims. (Cl. 223—67)

1

This invention relates to apparatus for shaping, finishing and otherwise conditioning garments, such as coats, and more particularly to a relatively porous bag supported by apparatus comprising a form, the bag being adapted to receive a garment thereover and held in suitable position while steam and/or hot air or other fluid garment conditioning medium is blown outwardly through the bag and garment.

Heretofore garment finishing apparatus of different types have been proposed, and this application relates to improvements in such apparatus. It is important in apparatus of this kind that the coat or other garment to be conditioned be shaped in the proper places and not overstretched in certain portions while understretched in others.

The principal objects of the present invention are to provide a form of this character having a bag adapted to prevent excessive ballooning around the breast and shoulder portions of the garment; to prevent steam from escaping from the front of the garment, such as a coat, and particularly between the lapels thereof during conditioning of the garment; to provide a bag of this character having a strip of impermeable material extending from the neck portion of the form and extending downwardly to lie underneath the open portion between the lapels of the garment; and to provide means for anchoring the strip of impermeable material to the form.

Other objects of the invention are to provide a bag which may be quickly and easily detached from and attached to the form; to provide means for attaching the bag to the bottom of the form to prevent escape of steam and/or air therefrom; and to provide a clamp in combination with the bag confining means which is simultaneously adjustable automatically to control the shape of the bag near the bottom of the garment.

Other objects of the invention are to provide a form that is simple and inexpensive to construct and which is readily operated to support a garment over a permeable bag.

In accomplishing these and other objects of the present invention, we have provided improved details of structure, the preferred form of which is illustrated in the accompanying drawings, wherein:

Fig. 1 is a perspective view of a garment finishing machine embodying the features of the present invention with the strip of impermeable material on the front of the bag shown in dotted lines.

Fig. 2 is a perspective view of the present in-

2

vention showing a coat supported on the form ready to be conditioned.

Fig. 3 is a vertical sectional view of the upper portion of the bag particularly illustrating the straps for resiliently anchoring the front and back of the bag to the form.

Fig. 4 is a perspective view of the invention as illustrated in Fig. 1 with parts broken away to better illustrate the anchoring means for the impermeable strip in front of the garment and the means for fastening of the bag to the lower portion of the form.

Fig. 5 is a vertical sectional view of the lower portion of the form particularly illustrating the means for fastening the bag to the form.

Referring more in detail to the drawings:

1 designates a garment finishing apparatus embodying the features of our invention and especially adapted for finishing coats and the like, although the upper portion of dresses may be conditioned if desired. The apparatus includes a base 2 for containing a source of heated air under pressure, such as a motor actuated blower (not shown), steam supply lines and valves (also not shown) for controlling flow of steam and air into a form comprising a hollow post or support 3 projecting upwardly from the base, having mounted upon the upper end of the support 3 by bolts or the like 4 a neck supporting element 5 which includes a neck portion 6, laterally extending shoulders 7, a breast portion 8, and back portion 9 generally conforming to the corresponding parts of the wearer of a garment to be finished on the machine.

35 The neck element 5 suspendingly supports a permeable bag 10 having the general shape of a garment at the upper portion thereof and the lower end being open and provided with a drawstring 11 as illustrated in Fig. 4. The upper portion of the bag is provided with a neck 12 which extends over the neck element of the support and includes a breast portion 13, back 14, and arms 15 and 16.

Secured to the underneath side of the breast portion 13 of the bag and extending over the neck portion 12 is a strip of impermeable material 17 secured to the front portion of the bag by stitching or other suitable means as indicated at 18. The back portion 19 of the strip is also secured to the back of the bag as best illustrated in Fig. 3 and this back portion is made of a permeable material. The front portion 17 of the strip of material extends to slightly below the breast portion of the bag. The back portion extends to substantially midway of the bag 10 and

to the respective corners of the strip 19 are attached coil springs 20. Secured to the lower end of the coil springs 20 are cords, wires or the like 21 having their lower ends secured to the post 3 in any suitable manner as illustrated in Fig. 3.

Attached to the under side of the strip of impermeable material 17 by stitching, as indicated at 22 (Fig. 4), or other suitable means, is a strip of permeable material 23. Secured to the respective lower corners of the strip 23 are coil springs 24. Attached to the lower ends of the coil springs 24 are cords or wires 25 having their lower ends also secured to the post 3 in any suitable manner as illustrated in Figs. 3 and 4.

A band of sheet material or the like 26 is secured to the post 3 or a bead formed therein a short distance above the base 2 as best illustrated in Fig. 5. The open end 27 of the bag 10 having the drawstring 11 is turned inwardly and upwardly and the drawstring 11 tightened so as to securely engage the post 3 above the band 26 to prevent air and steam escaping through the open end of the bag as it flows through the post 3. The lower end of the bag 10 is slit and provided with a zipper 28 (Fig. 4) so as to provide a large open end to the bag 10 to facilitate placement of the bag over the form.

A weight 29 is placed in the loop portion 30 of the lower end of the bag to prevent the bag from ballooning upwardly when air and steam is admitted to the interior thereof. The weight 29 may be of any suitable material, such as a steel ring, chain or the like, and of a sufficient weight to prevent undue ballooning of the bag. A ring 31 circles the lower portion of the bag to further prevent undue ballooning of the bag.

Supported on the base 2 parallel with the tubular post 3 is a standard 32. Slidably mounted on the standard 32 is a bracket member 33 provided with a handle 34. On the upper end of the bracket 33 is pivotally mounted a movable clamping plate 35 adapted to engage the front of the garment to be conditioned as best illustrated in Fig. 2 to prevent excessive ballooning of the coat and steam escaping from the front portion of the garment where it buttons together. The bracket 33 engages the ring 31 so that when the plate is adjusted on the standard the ring will also be moved on the bag to confine the bag and prevent undue ballooning thereof.

Operation of a device constructed and assembled as described is as follows:

A garment, such as a coat, 36 is first placed over the bag 10 of the form, the arms 15 and 16 of the bag being tucked into the sleeves 37 and 38 of the coat. The front of the coat is then buttoned, the plate 35 having previously been pulled away from the form by downward pressure on the handle 34. The clamping member is then adjusted on the standard to the desired height so that the lower end of the plate 35 will be slightly below the lower edge of the garment, and manipulation of the handle 34 will cause the plate to be firmly held against the front portion of the coat, the coat being held between the bag 10 and the plate. The bracket of the clamping member is provided with suitable means for attaching the ring 31 thereto so that the ring will be adjusted to position along with the clamping plate to hold the bottom of the coat in place to prevent its being flared outwardly when the bag 10 is inflated.

Hot air is forced into the tubular support 3 and will enter the interior of the bag through a plurality of longitudinal openings 39 around the

tubular post near the upper portion thereof and through the upper open end 40 of the tube so that the interior of the bag may be filled with the steam and air as desired, and thence will be forced out through the bag and the fabric of the coat by manipulation of the foot levers 40 and 41 (Fig. 1). The steam or air may be introduced simultaneously or selectively as desired.

The impermeable strip 17 extending over the breast portion of the bag will lie underneath the open portion of the coat between the lapels 42 and 43 and thus prevent escape of steam and air therethrough to facilitate ballooning of the bag and at the same time prevent steam from escaping to contact the operator of the apparatus. The back portion 19 is made of permeable material so that the steam and air will permeate therethrough and through the bag to the garment. The lower portion 44 of the back strip 19 having the springs attached thereto and anchored to the tubular post will tend to prevent undue ballooning of the back of the garment and the strip 23 and springs 24 attached to the impermeable strip 17 will prevent undue ballooning of the breast portion of the garment, at the same time providing sufficient resiliency to allow proper ballooning of the bag and consequently the garment. The weight 29 in the bottom of the bag will prevent the bag from climbing upwardly when steam or air is admitted to the interior of the bag, and the ring 31 being positioned slightly below the lower edge of the coat will prevent undue ballooning of the bag just below the lower edge of the coat, thus preventing an objectionable outward flare at the lower edge. The clamping plate 35 will also prevent undue ballooning and at the same time prevent undesired creases in the front portion of the coat.

We have found it desirable to emit the steam from the tubular member 3 at substantially the center of the coat to be conditioned or slightly thereabove as some of the steam and air will be emitted through the open top 40, the major portion, however, entering the garment through the openings 39 around the periphery of the tube.

It will be apparent, of course, that our invention is not restricted to the details and particular structure of apparatus illustrated. Various changes may be made in this structure as will be apparent to those skilled in the art without sacrificing the advantages described.

It will be obvious from the foregoing that we have provided an improved bag for conditioning garments, such as coats, to prevent undue ballooning thereof and prevent escape of steam and air between the lapels of the coat, as well as a bag which may be quickly and easily removed from the form for replacement or repair.

What we claim and desire to secure by Letters Patent is:

1. An apparatus for finishing garments having an open portion therein, a form having a breast and back portion, a flexible, permeable covering for said form, means for discharging a fluid medium inside said covering, and means engaging said covering adapted to underlie said open portion of the garment underneath said covering to prevent the fluid medium from escaping there-through.

2. An apparatus for finishing garments having an open portion, a form having a breast and back portion, a flexible, permeable covering for said form, means for discharging a fluid medium inside said covering, and means engaging the inside of said covering adapted to underlie said open

portion of the garment underneath said covering to prevent the fluid medium from escaping therethrough.

3. An apparatus for finishing garments having an open breast portion, a form having a breast and back portion, a flexible, permeable covering for said form, means for discharging a fluid medium inside covering, and means engaging the inside of said covering adapted to underlie said open breast portion of the garment underneath said covering to prevent the fluid medium from escaping therethrough.

4. An apparatus for finishing garments having an open portion, a form having a breast and back portion, an inflatable, permeable covering for said form, means for discharging a fluid medium inside said covering, means engaging said covering adapted to underlie said open portion of the garment underneath said covering to prevent the fluid medium from escaping therethrough, and resilient means engaging said form and said first-named means for limiting inflation of the bag around the breast and back portion of the garment.

5. An apparatus for finishing coats or the like having an open breast portion, a form having a breast and back portion, an inflatable, permeable bag covering said form, means for discharging a fluid medium inside said bag to inflate the same, a strip of material extending over the breast portion of said form underneath said bag, said strip being of impermeable material and adapted to underlie the open breast portion of the coat, and means engaging the ends of said strip and said form for limiting inflation of said bag around the breast portion.

6. An apparatus for finishing coats or the like having an open breast portion, a form having a breast and back portion, an inflatable, permeable bag covering said form, means for discharging a fluid medium inside said bag to inflate the same, a strip of material extending over the breast and back portions of said form underneath said bag, the breast portion of said strip being of impermeable material and adapted to underlie the open breast portion of the coat, and means engaging the ends of said strip and said form for limiting inflation of said bag around the breast and back portions.

7. An apparatus for finishing coats or the like having an open breast portion, a form having a breast and back portion, an inflatable, permeable bag covering said form, means for discharging a fluid medium inside said bag to inflate the same, a strip of material extending over the breast and back portions of said form underneath said bag, the breast portion of said strip being of impermeable material and adapted to underlie the open breast portion of the coat, and resilient means engaging the ends of said strip and said form for limiting inflation of said bag around the breast and back portions.

8. An apparatus for finishing coats or the like having an open breast portion, a form having a breast and back portion, an inflatable, permeable bag covering said form, means for discharging a fluid medium inside said bag to inflate the same, a strip of material extending over the breast and back portions of said form underneath said bag, the breast portion of said strip being of impermeable material and adapted to underlie the open breast portion of the coat, and coil springs engaging the ends of said strip and said form for limiting inflation of said bag around the breast and back portions.

9. An apparatus for finishing coats or the like having an open breast portion, a form having a breast and back portion, an inflatable, permeable bag covering said form, means for discharging a fluid medium inside said bag to inflate the same, a strip of material extending over the breast and back portions of said form underneath said bag, the breast portion of said strip being of impermeable material and adapted to underlie the open breast portion of the coat, means engaging the ends of said strip and said form for limiting the inflation of said bag around the breast and back portions, and means engaging said bag below said coat to limit the inflation of said bag to prevent outward flare of the bottom of said coat.

10. An apparatus for finishing coats or the like having an open breast portion, a support, a form having a breast and back portion, an inflatable, permeable bag having an open bottom for covering said form, means for discharging a fluid medium inside said bag to inflate the same, means on said open end of the bag for fastening the bag to the support, a strip of material extending over the breast and back portions of said form underneath said bag, the breast portion of said strip being of impermeable material and adapted to underlie the open breast portion of the coat, and means engaging the ends of said strip and said form for limiting the inflation of said bag around the breast and back portions.

11. An apparatus for finishing coats or the like having an open breast portion, a support, a form having a breast and back portion, an inflatable, permeable bag having an open bottom for covering said form, means for discharging a fluid medium inside said bag to inflate the same, means on said open end of the bag for fastening the bag to the support, a strip of material extending over the breast and back portions of said form underneath said bag, the breast portion of said strip being of impermeable material and adapted to underlie the open breast portion of the coat, means engaging the ends of said strip and said form for limiting the inflation of said bag around the breast and back portions, and means engaging said bag below said coat to limit the inflation of said bag to prevent outward flare of the bottom of said coat.

12. An apparatus for finishing coats or the like having an open breast portion, a support, a form having a breast and back portion, an inflatable, permeable bag having an open bottom for covering said form, means for discharging a fluid medium inside said bag to inflate the same, means on said open end of the bag for fastening the bag to the support, a strip of material extending over the breast and back portions of said form underneath said bag, the breast portion of said strip being of impermeable material and adapted to underlie the open breast portion of the coat, means engaging the ends of said strip and said form for limiting the inflation of said bag around the breast and back portions, means engaging said bag below said coat to limit the inflation of said bag to prevent outward flare of the bottom of said coat, said open end of the bag being split, and a zipper fastener for said slit whereby opening of the zipper will facilitate placement of the bag over the form.

13. An apparatus for finishing coats or the like having an open breast portion, a form having a breast and back portion, an inflatable, permeable bag covering said form, means for discharging a fluid medium inside said bag to inflate the same, a strip of material extending over the

breast and back portions of said form underneath said bag, the breast portion of said strip being of impermeable material and adapted to underlie the open breast portion of the coat, means engaging the ends of said strip and said form for limiting the inflation of said bag around the breast and back portions, means engaging said bag below said coat to limit the inflation of said bag to prevent outward flare of the bottom of said coat, and clamping means to hold the lower portion of a garment placed over said bag.

14. An apparatus for finishing coats or the like having an open breast portion, a form including a support having a breast and back portion, an inflatable, permeable bag covering said form, means for discharging a fluid medium inside said bag to inflate the same, a strip of material extending over the breast and back portions of said form underneath said bag, the breast portion of said strip being of impermeable material and adapted to underlie the open breast portion of the coat, resilient means engaging the ends of said strip and said support for limiting the inflation of said bag around the breast and back portions, means engaging said bag below said coat to limit the inflation of said bag to prevent outward flare of the bottom of said coat, and clamping means to hold the lower portion of a garment placed over said bag.

15. An apparatus for finishing coats or the like having an open breast portion, a support, a form
